United States Patent Office

Des. 183,155

Patented July 8, 1958

183,155

PUNCH

Vytant Aleks, Rockford, Ill., assignor to Apesco Products, Inc., Los Angeles, Calif., a corporation of Illinois

Application November 12, 1957, Serial No. 48,406

Term of patent 14 years

(Cl. D74—1)

Fig. 1 is a top plan view of a punch, showing my new design;

Fig. 2 is a front elevational; and

Fig. 3 is a side elevational view thereof.

I claim:

The ornamental design for a punch, as shown.
